2 SHEETS-SHEET 2.

UNITED STATES PATENT OFFICE.

EUGENE BOUILLET, OF LONG ISLAND CITY, NEW YORK.

AERONAUTICAL APPARATUS.

1,084,248.

Specification of Letters Patent. Patented Jan. 13, 1914.

Application filed December 4, 1912. Serial No. 734,833.

To all whom it may concern:

Be it known that I, EUGENE BOUILLET, a citizen of France, residing at Long Island City, in the county of Queens and State of New York, have invented certain new and useful Improvements in Aeronautical Apparatus, of which the following is a specification, reference being had therein to the accompanying drawing.

10 My invention relates to improvements in aeronautical apparatus and has particular reference to aeroplanes and more particularly to a tri-plane.

15 In the accompanying drawings I have illustrated in plan view in Figure 1 one application of my invention with parts omitted. Fig. 2 is a front elevation of the same. Fig. 3 is a detail of one of the ribs of one of the surfaces. Fig. 4 is a detail of 20 controlling means for operating some of the balancing surfaces, and Fig. 5 is a detail of a modification in perspective.

25 5—6 are the upper main supporting surfaces, 7—8 are the intermediate supporting surfaces, 9—10 are the lower main supporting surfaces, and 11 are the connecting bars or rods forming the tri-plane structure.

30 12—13 are parallel longitudinally extending bars of the framework connecting the tail section comprising the surfaces 14—15—16.

35 17 and 18 are lateral surfaces connected to the longitudinal bars 12 and 13 which may be used for maintaining equilibrium as will be hereafter more fully described.

40 19 is a fixed intermediate surface just forward of the tail.

20 20 is the elevator pivoted upon the bars 21—22 and may be inclined by any suitable 45 means such as the connecting wire 23 within convenient reach of the operator.

25 24 is the hand wheel adjacent to the seat 45 and connected with the rudder 26 by the wires 27—27' as shown so that by rotating the wheel 24 the rudder 26 may be operated in the usual well known manner, and by throwing the wheel 24 forward and backward the elevator 20 may be raised and lowered by the connecting wire 23 also in the 50 usual well known manner.

55 The surfaces 17 and 18 are connected by the rod 28 as shown to advantage in Fig. 4 and this rod is connected by wires 29—29' to the lever 30 at the right of the operator's seat so that by operating said lever the surfaces 17—18 may be raised on one side and

lowered on the other as shown in dotted outline in Fig. 4, thus serving to maintain equilibrium. The tail surface 14—15—16 is mounted upon the axis 31 which in turn is connected by the wire or cable 32 to the lever 33 at the left side of the operator's seat which when thrown forward or rearward serves to elevate or depress the tail according to the will of the operator.

65 At the lateral extremities of the intermediate supporting surfaces 7—8 suitable ailerons or balancing surfaces such as 34—35 may be pivotally mounted as shown and connected by any suitable means such as the 70 bar 36 which in turn is pivoted to the bar 37 pivoted to the lever 38, pivotally mounted in the bracket 39 and within convenient reach of the operator, so that by shifting the lever 38 the ailerons can be readily operated.

75 In Fig. 3 the preferred cross sectional curve of the supporting surfaces is shown. In Fig. 1 the intermediate surface is shown in dotted outlines as indicated by the reference character 7 on the left hand side of 80 said figure. On the right hand side of said figure the lower supporting surface is shown in dots and dashes and indicated by the reference character 10.

85 40—41 are pontoons having cut away portions at the center to admit of the wheels 42—43 and connected by the bar 44. This bar is in turn connected with the bar 45 and the levers 46, 47 and 48 so that by lifting the lever 48 the bar 47 and its connecting 90 bar 46 are rotated which lifts the rod 45 and the connecting bar 44, raising the pontoons clear of the wheels 43 so that said 95 wheels can run upon the ground when the pontoons are not in use.

49 and 50 are suitable tanks which may be provided with oil, and 51 is a smaller tank in the upper part of the machine into which the oil may be forced to supply the engine 52.

53 is the propeller.

100 Referring now to Fig. 5, 54 indicates an intermediate surface which may be substituted for the surface 7—8 although it is preferable that the intermediate surface should not be quite as wide as shown in Fig. 2. In 105 the form of surface shown in Fig. 5, it will be observed that this surface appears in plan to resemble the top supporting surface shown in Figs. 1 and 2 except that the tip 55 is mounted upon the axis 56 which is 110 adapted to be rotated by the operator in any suitable manner so that the ailerons or tips

55 on either side of the machine can be tilted for balancing purposes.

Of course it will be understood that various modifications may be made without departing from the spirit of the invention as set forth in the claims.

I claim:

1. In a triplane, an upper supporting surface having rearwardly projecting lateral tips, an intermediate supporting surface having controlling surfaces mounted in the lateral extremities thereof, and a rectangular lower supporting surface.
2. In a triplane, an upper supporting surface having rearwardly projecting lateral tips, an intermediate supporting surface having controlling surfaces mounted in the lateral extremities thereof, and a rectangular lower supporting surface, said intermediate surface of less width than said upper supporting surface, and said lower supporting surface of less width than said intermediate supporting surface.
3. In a triplane, an upper supporting surface having rearwardly projecting lateral

tips, an intermediate supporting surface having controlling surfaces mounted in the lateral extremities thereof, and a rectangular lower supporting surface, said surfaces having substantially flat forward and rearward portions and an arched central portion extending transversely of the same.

4. In a triplane, an upper supporting surface having rearwardly projecting lateral tips, an intermediate supporting surface having controlling surfaces mounted in the lateral extremities thereof, a rectangular lower supporting surface and an elevator pivotally mounted in the center of said upper supporting surface and at the forward portion of the same adapted to be adjusted upon an axis transverse to the line of flight.

In testimony whereof I affix my signature in presence of two witnesses.

EUGENE BOUILLET.
